UNITED STATES PATENT OFFICE

94,722

DESIGN FOR A JUG OR SIMILAR ARTICLE

John S. Algeo, Wheeling, W. Va., assignor to Hazel-Atlas Glass Company, Wheeling, W. Va., a corporation of West Virginia

Application December 3, 1934, Serial No. 54,249

Term of patent 14 years

To all whom it may concern:

Be it known that I, John S. Algeo, a citizen of the United States, residing at Wheeling, in the county of Ohio and State of West Virginia, have invented a new, original, and ornamental Design for a Jug or Similar Article, of which the following is a specification, reference being had to the accompanying drawing, forming part thereof.

I claim:

The ornamental design for a jug or similar article, as shown.

JOHN S. ALGEO.
